UNITED STATES PATENT OFFICE.

BENJAMIN HOLT, OF CAMDEN, NEW JERSEY.

KNITTING-MACHINE.

SPECIFICATION forming part of Letters Patent No. 448,718, dated March 24, 1891.

Application filed October 7, 1889. Serial No. 326,185. (No model.)

To all whom it may concern:

Be it known that I, BENJAMIN HOLT, a citizen of the United States, and a resident of Camden, New Jersey, have invented certain 5 Improvements in Knitting-Machines, of which the following is a specification.

My invention consists of an improvement in knitting-machines of the class shown in the application of Salisbury and Wrightson, 10 filed January 14, 1889, Serial No. 296,303, one feature of my invention being a substitute for the laterally-movable cam which in the Salisbury and Wrightson machine is employed in connection with bits of graded length on the 15 needles to effect the dropping out of action or the bringing into action of certain of the needles of the machine, and a further feature of my invention being the means whereby the needles out of action are freed from the influence of the drawing-down cam, so that the 20 stitches carried by these needles are not subjected to strain and wear.

In the accompanying drawings, Figure 1 is a sectional view of part of the needle-cylinder 25 and cam-box of a circular-knitting machine constructed in accordance with my invention. Fig. 2 is a view, partly in elevation and partly in section, of part of the cylinder and cam-box of the machine and of parts carried by the 30 latter. Fig. 3 is a sectional top view, partly in elevation, of part of the cam-box. Figs. 4, 5, and 6 are detached views of some of the needle-jacks. Figs. 7, 8, and 9 are views of parts of the cam-operating mechanism. Fig. 35 10 is a detached view showing the needle-lifting cams in their inoperative position. Fig. 11 is a sectional view of part of the needle-cylinder. Fig. 12 is a sectional view of part of a knitting-machine of modified construction 40 containing some of the features of my invention. Figs. 13 and 14 are longitudinal sectional views of part of the cam-box and needle-operating cam forming part of said machine, the cam being shown in different positions in the two views. Fig. 15 is a sectional view of the cam-box with the improved cam in elevation. Fig. 16 is a sectional view of part of the machine. Fig. 17 is a view illustrating a modification, and Fig. 18 is a diagram 45 illustrating means for operating the cam-actuating bar of the machine shown in Figs. 12 to 16.

In the machine shown in the Salisbury and Wrightson application above referred to a certain number of needles at each end of the 55 set on which the narrowing and widening were to be performed were provided with bits graded in length, and the cam for actuating the needles was guided in the cam-box so as to be free to move toward and from the needle-carrier, so that as it was moved outward it passed by successive steps beyond the range of the successive graded bits and when moved inward was brought into range of these graded bits successively. In order to dispense 60 with the necessity for this movement of the cam from and toward the needle-carrier, I use a compound cam composed of a number of sections each of a width equal to the difference between the lengths of successive bits of 65 the graded series, as many of these sections being employed in the cam as there are graded bits in the series and the sections being pivoted, so that when they occupy an elevated position they will act upon the bits to raise the 70 same and the needles, but when in a depressed or lowered position will fail to so act.

In Fig. 1, A represents part of the needle-cylinder, x the needles of the same, and y the projecting bits of the needle-jacks, each of the 80 needle-jacks having an upper movable portion y', for a purpose described hereinafter, and the needle-cylinder having projecting arms A', connected at the outer end by a ring A², and having upwardly-projecting guide-fingers A³ for the bits of the needle-jacks, as 85 shown in Fig. 11.

The needle-cylinder A is mounted so as to be free to turn either continuously forward or first forward and then backward in a bearing a of the fixed frame or bed B of the machine, and mounted on this fixed frame is a cam-box D, carrying the cams for elevating and depressing the needles of the cylinder.

There are in the present instance two lifting-cams E E and a single central drawing-down cam F, one of the lifting-cams serving to raise the needles when the cylinder is moved in one direction and the other serving to raise the needles when the cylinder is moved in the opposite direction, the drawing-down cam acting in either case. Each of the cams E is composed of one-half as many sections w as there are graded bits on the jacks

of the needles constituting the fashioning-set, these cam-sections being hung to transverse pins *b*, carried by the cam-box, and being normally held in position to engage with the bits of the needles, as shown at the right-hand side of Fig. 2, so that the contact of the moving bit with the projecting portion of the cam will cause the latter to swing upward on its pivot to the full operative position, as shown at the left-hand side of said figure, the means employed in the present instance for holding the sections of the cam in operative position being a plate *d*, secured to the cam-box and having as many elastic fingers *f* as there are sections in each cam, each of these fingers having at the outer end a block *g* for acting upon the tail ends of the sections of the cams with which it coincides, and having also a stud *i* bearing upon the periphery of a disk *h*, which is mounted upon a shaft or spindle *j*, adapted to bearings in the fixed frame of the machine, there being one disk for each pair of cam-sections, and the disks turning with the shaft *j* as the latter is intermittently rotated through the medium of a ratchet-wheel *k* and vibrating lever *k'*, carrying a spring-pressed pawl *k*² for engaging with the ratchet-wheel, as shown in Figs. 1 and 2. Various means may be employed for vibrating this lever, one such means being shown by dotted lines in Fig. 1, in which the lever is bent inward for the action of an arm projecting from the lower portion of the needle-cylinder, it being understood that the latter is provided with two of these arms, one for striking the lever and moving it in one direction at one limit of the vibration of the cylinder and the other for striking the lever and moving it in the opposite direction at the opposite limit of vibration of the cylinder.

If all of the sections of the cams are elevated, all of the needles will be acted upon as their bits are carried over the cams; but if the innermost section of each cam is allowed to drop the needle or needles having the shortest bits, which do not extend beyond the first sections of the cams—as in Fig. 4, for instance—will remain out of action, and by the dropping of successive sections of the cams the needles may be gradually dropped out of action until all the needles having graded bits have been thus rendered inoperative, whereupon by again raising the sections of the cams in reverse order the needles having graded bits may be brought into action again in an order the reverse of that in which they were allowed to drop out of action.

In order to provide for dropping the successive sections of the cams and subsequently raising the same, the disks controlling the cam-actuating fingers *f* have steps and recesses graduated in extent, so as to allow the cam-sections controlled thereby to remain out of action for a longer or shorter time, depending upon the radial position of said cam-sections in respect to the cylinder. For instance, the disk 1, Fig. 7, controlling the innermost

sections of the cams, will be recessed throughout almost its entire periphery, having a projecting step *s* of limited dimensions, which serves to hold the innermost sections of the cams in operative position during the normal working of the machine for the production of tubular fabric, but which on the first movement of the shaft *j* to commence the narrowing and widening operation drops said sections of the cams out of action and allows them to remain out of action until the narrowing and widening have been completed, the last movement of the shaft *j* on the completion of the widening operation bringing the innermost sections of the cams into operative position again. The next disk has a recess of somewhat less extent, and hence a supporting-step of somewhat greater length, and so on. For instance, in the intermediate disk 10, Fig. 8, the supporting-step and the recess are about equidistant in extent, and the outermost disk 20, Fig. 9, has a contracted recess about equaling in extent the supporting-step of the disk 1, so that the outermost sections of the cams, when dropped out of action on the completion of the narrowing, will on the next movement of the shaft *j* be again brought into action to start the widening.

If the fashioning-needles which are out of action are on each reciprocation of the needle-cylinder brought under the control of the drawing-down cam *F*, the repeated movements of these needles, even though slight, has a tendency to wear the loops or stitches carried by the needles and subject them to undue strain, which may cause them to break. I therefore provide for releasing the fashioning-needles which are out of action from the influence of the drawing-down cam. This cam acts upon the radially-sliding portion *y'* of each jack and on the inner portion of the cam-box on each side of the drawing-down cam *F*, and beyond the lifting-cams *E* are cams *G*, while on the outer portion of the cam-box is a central cam *H*, extending laterally some distance to each side of the drawing-down cam *F*. (See Fig. 3.)

The cams *G* so act upon the sliding portions *y'* of the jacks that before said jacks reach the lifting-cams *E* said sliding portion *y'* of the jack will be pushed outward to such an extent that it will not come under the influence of the drawing-down cam *F*. If the jack is not raised by the lifting-cam, the outer end of the sliding portion *y'* of the jack will pass beneath the cam *H*. Hence said slide will remain beyond the drawing-down cam, and the jack will not be acted upon thereby. If, however, the jack is raised by the lifting-cam, the outer end of its slide will be brought under the influence of the cam *H*, and said slide will be thereby pushed inward, so as to bring its inner end under control of the drawing-down cam.

In the simpler form of machine embodying my invention, which I have shown in Figs. 12 to 16, the means for releasing the jacks

from the control of the drawing-down cam are dispensed with, and a single lifting-cam E', operating to raise the needles on either movement, is substituted for the two lifting-cams shown in Fig. 2, it being understood that the drawing-down cam in this case is duplex, so as to draw down the jacks which have been elevated by either face of the lifting-cam.

10 The machine shown in Figs. 12 to 16 is a straight machine having a reciprocating cam-box D', and the operation of the sections w' of the cam is effected by a stepped lifter-bar h', mounted on the cam-box so as to move therewith, but free to move longitudinally thereon, the steps being so arranged that by moving this bar longitudinally on the cam-box in one direction the sections of the cam will be successively lowered, and by moving it in the opposite direction said cam-sections will be successively raised in the reverse order. The movement of the bar h' may be effected by pattern-chains P acting upon the ends of the bar as the latter is carried to right 25 and left on the reciprocating cam-box D', the links of the chain varying in height, so as to effect the desired series of intermittent movements of the bar first in one direction and then in the opposite direction. A device of this 30 character is shown in the diagram Fig. 18.

It is not necessary in carrying out my invention that the cam-sections should in all cases be pivoted, as said sections may, as will be evident, be guided so as to slide vertically, 35 and the steps of the lifting device or the lower ends of the cam-sections, or both, may be beveled, so as to effect the raising of the cam-sections on the movement of the lifter. (See Fig. 17.)

40 Having thus described my invention, I claim and desire to secure by Letters Patent—

1. The combination of the needle-carrier having needles with graded bits with a needle-operating cam composed of a series of 45 sections free to move independently of each other to operative or inoperative position and means to effect such movement, whereby the needles having graded bits may be thrown into or out of action by the movement of the 50 sections of the cam, substantially as specified.

2. The combination of the needle-carrier having needles with bits graded in length with a needle-operating cam composed of sections movable independently of each other 55 to operative or inoperative position and a stepped lifter for acting upon the sections successively and moving them into operative or inoperative position, substantially as specified. 60

3. The combination of the needle-carrier having needles with bits graded in length, a needle-operating cam composed of sections movable independently of each other to operative or inoperative position, blocks for acting 65 on said cam-sections, and stepped disks for actuating said blocks, substantially as specified.

4. The combination of the lifting and drawing-down cams, the needles having jacks with 70 portions movable into and out of range of the drawing-down cam, and cams for acting upon said movable portions of the jacks to so move them into and out of range, substantially as specified. 75

In testimony whereof I have signed my name to this specification in the presence of two subscribing witnesses.

BENJAMIN HOLT.
